UNITED STATES PATENT OFFICE.

THOMAS J. LOFTUS, OF SACRAMENTO, CALIFORNIA.

STRAIGHTWAY VALVE.

SPECIFICATION forming part of Letters Patent No. 248,482, dated October 18, 1881.

Application filed July 18, 1881. (No model.)

To all whom it may concern:

Be it known that I, THOMAS J. LOFTUS, of the city and county of Sacramento, California, have invented an Improved Straightway Valve, of which the following is a specification.

The object of my invention is to provide a new and improved straightway valve which will close very tightly, and in which the slides or gates will not grind on the sides of the casing.

10 The invention consists in a valve casing with two ports, one at each end, and with a projection at each side, this casing containing two sliding gates with conical recesses in the adjoining sides, which recesses contain a conical

15 wedge swiveled in the lower end of the screw valve-stem, which is provided at its lower end with an annular flange, also contained within the recesses and overlapped by shoulders at the upper ends of the gates. The gates are

20 lowered by means of the valve-stem until they rest on the projections of the casing, and are then spread and pressed against the ends of the casing by the swiveled conical wedge, so that they will close the ports tightly.

25 In the drawings, Figure 1 is a longitudinal sectional elevation of my improved valve. Fig. 2 is a cross-sectional elevation of the same. Fig. 3 is an elevation of the inner side of one of the gates. Fig. 4 is a plan view of the under side of the gates.

Similar letters of reference indicate corresponding parts.

The valve casing or box A is provided with the ports B B in the ends C C, and with internal projections, D D, in the sides, and with a screw-neck, E, for the screw valve-stem F, provided with a hand-wheel, G. This valve-casing

35 contains two sliding gates, H, with smooth outer surfaces, and with beveled or inverted conical recesses J in the inner or adjoining surfaces, with a shoulder, K, at the upper end of the recess, and shoulders N at the sides. A conical wedge, L, is swiveled to the lower end of the valve-stem F, provided at its lower end with an annular flange, M.

40 This conical wedge L and the annular flange M are contained in the aperture formed by the two recesses J, the shoulders K overlapping the flanges M, as shown. The conical wedge L may be rigidly attached to

45 the lower end of the stem, but I prefer to swivel it.

50 The operation is as follows: If the hand-wheel G is turned from left to right the stem or rod F descends, as do likewise the gates H,

until the shoulders N N of the gates rest on 55 the internal projections D of the casing A, thereby closing the ports B. If the hand-wheel is still turned the gates H cannot descend any farther on account of the projections D, but the wedge L descends and presses the gates 60 H against the ends C of the casing A, as indicated by the arrows, and thus closes the ports B very tight'y. If the hand-wheel G is turned from right to left the conical wedge L will first rise and then the flange M, which catches on 65 the shoulders K of the gates H, draws these gates upward and thus opens the ports. The gates cannot grind on the inner surfaces of the ends of the casing, as their movement is only a lateral one when they are pressed against 70 the ends of the casing, and replaning the outer surfaces will not cause them to drop any lower than before, as it does in the straightway valves in use heretofore. As the wedge L is swiveled to the lower end of the stem F it will not grind 75 on the surfaces of the recesses J when the stem F is turned, and only the upper annular surface of the wedge grinds on the lower annular surface of the stem, and then these two surfaces can wear off gradually without affecting 80 the close joint of the valve.

Having thus described my invention, I claim as new and desire to secure by Letters Patent—

1. In a straightway valve, the combination, 85 with the casing A, provided with valve-seats C C and ports B B, of the gates H H, provided with recesses J, shoulders K, conical wedge L, and valve-stem F, substantially as herein shown and described.

2. In a straightway valve, the combination, 90 with the gates H, provided with recesses J and shoulders K on their inner and adjoining surfaces, of the conical wedge L and valve-stem F, substantially as herein shown and described.

3. In a straightway valve, the combination, 95 with the casing A, provided with internal projections, D, of the gates H, provided with shoulders N in the sides, and shoulders K, and conical recesses J in the adjoining inner surfaces, of the valve-stem F, and the conical wedge L, 100 swiveled to its lower flanged end, substantially as herein shown and described, and for the purpose set forth.

THOS. J. LOFTUS.
